RESILIENT COUPLING FOR ABRASIVE WHEELS

Berne Tocci-Guilbert, San Francisco, Calif., assignor, by mesne assignments, to Berne Tocci-Guilbert, San Francisco, and Henry Gifford Hardy, Berkeley, Calif., jointly, as trustees

Application September 30, 1949, Serial No. 118,820

2 Claims. (Cl. 64—13)

1

This invention relates to constrictive means for modifying and limiting the vibratory oscillating torque of resilient couplings, particularly those of the type disclosed in the copending application bearing Serial No. 55,620, filed October 20, 1948, entitled Resilient Couplings.

Among the objects of the invention is the control of, and extending the usefulness of, means for introducing an oscillating or gyrating torque between the motor shaft and the abrasive assembly, to eliminate concentric and other scoring effects common in the use of flexible abrasive discs, cup wire brushes, flat emory wheels and the like.

A particular object is the control of the degree of oscillation in the coupling to render it adaptable to a wide range of applications in the abrasive art, from coarse planal grinding of flat surfaces, to the grinding and polishing of curved surfaces such as the fenders of automobile bodies and the like.

Another object is the introduction of a structure and mode of operation adapted to overcome the tendency of revolving grinding wheels and discs, to jump laterally out of control when the revolving grinder is applied to a stationary surface, especially a flat surface. Such loss of control of the grinding assembly often results in injury to the surface being ground and to the operator.

Couplings having a rubber-like cushion interposed between the driving and driven elements, containing a sufficient mass of cushion to be efficient in relatively light abrasive operations, get out of control at grinding speeds when coarser grits are used, and especially when heavier, rigid grinding wheels are substituted for the flexible abrasive discs.

The present invention results in the reduction of skill and experience required by the operator, to safely practice the art of manually applying a portable grinder to the surfaces to be reduced by abrasion when relatively heavy stones or cup wire brushes are used.

Broadly stated, the present invention comprises an external band encircling the oscillating cushion of a resilient coupling for reducing the range of oscillation of said cushion, while at the same time increasing the modulus. The use of the present invention permits employment of an oscillator designed to operate at speeds up to 5000 R. P. M. with one pound of weight maximum, to carry loads up to five and six times greater than the maximum, all with perfect safety. The increase in modulus produces a much higher rate

5 of gyrations than originally intended for the oscillator with the lighter maximum load, again all with perfect safety to the operator and the work. This becomes especially important where the tool has a pneumatic motor with variable speeds up to greatly in excess of 5000 R. P. M., such as are used on fine surfaces or very soft surfaces such as marble, cork, linoleum, etc.

Other objects and advantages will appear as 10 the description proceeds. In the specification and the accompanying drawings the invention is disclosed in its preferred form. But, it is to be understood that it is not limited to this form because it may be embodied in modifications within the spirit of the invention as defined in the claims following the description.

In the drawings:

Figure 1 is a vertical section showing a resilient coupling having this invention applied thereto as 15 an accessory.

Figure 2 is perspective of the constrictive cup for encircling the coupling cushion, looking into its completely open end.

Figure 3 is a view similar to Figure 1, with a 20 solid grinding wheel substituted for the flexible grinding disc.

In detail, the structure shown in Figure 1 comprises the motor 11, having the reduction gear case 12, with the threaded hub 13 of the driving gear projecting therefrom and functioning as 25 the driving shaft of the coupling. The continuation of the motor unit not shown, normally terminates in a longitudinal handle, from which the service cable extends to the source of power. The motor housing has the side handle 12' for 30 two-handed control of the motor unit.

The structure of the resilient coupling comprises the substantially flat driving head 15 having an internally threaded hub 14 and a concentric peripheral flange 16, undercut as at 17. The hub 14 has an annular flange 18 projecting 35 radially therefrom.

The driven head 19, in opposed relation to the driving head 15, has the similar peripheral flange 20, undercut at 21 and integral with the internally threaded hub 22 that is axially aligned with the driving hub 14. The face 23 of the head 19 is preferably countersunk with the taper extending inwardly toward the hub 22. This hub 40 also has the annular flange 24 projecting radially therefrom.

The space between the heads 15 and 19 is 45 filled with a rubber-like, resilient material 25 vulcanized therein and adhering to all contacting surfaces, or is otherwise secured therein in any 50

suitable manner. The bonding of the resilient material to the heads, hubs, and flanges forms a unitary structure capable of transmitting torque. The resilient material 25 is keyed to the driving head 15 by its mass within the radial flange 18 and the undercut peripheral flange 16, and to the driven head 19 by the mass between the radial flange 24 and the undercut peripheral flange 20. The resilient body 25 includes a continuous web 25' which passes between the flanges 18 and 24 and provides an extended area against which the flanges may work. The resilient material which separates the driving and driven heads extends flush with the perimeters of the inturned flanges 16 and 20 to form an integral flexible coupling to the drive shaft 13 against the shoulder of which the hub 14 abuts. The torque of the drive shaft 13 is transmitted to the driven head 19 by the resilient cushion 25. It will be observed that the resilient cushion 25 is in shear normally with the respect to the driving head 15 and the driven head 19.

The flexible plate, or back pad, 26 has the depressed center portion 27 fitting snugly within the dished surface 23. This plate, or back pad 26, is composed of any suitable material such as a plastic sheet, fibre, rubber, non-fatiguing metal or the like and serves as a backing plate for the abrasive disc 28.

The abrasive disc 28 is free of grit centrally so that it may be depressed to conform to the countersunk or dished surface 23 of the driven plate 19. The abrasive disc 28 and backing plate 26 are held in working position by the head 29 of the nut 30, threaded into the driven hub 22. Tightening the nut 30 causes the plate 26 and disc 28 to conform to the dished surface 23. These discs are usually composed of plastic or fibrous sheet material coated on one or both sides with a plastic binder into which a granular abrasive is embedded the cutting qualities of which range from coarse to the finer grades for polishing.

The particular machine shown in the drawing, equipped with the oscillator, is manipulated by grasping the two handles on the housing of the motor unit with both hands and applying the whole exposed face of the disc 28 to the surface to be worked, rather than leading peripheral edge only, with manually applied pressure. To prevent burning the surface the disc 28 is constantly moved over the surface. The greater the pressure applied to the disc 28 the greater the deviating eccentricity resulting in the oscillating orbit, making it practically impossible to form concentric score lines in the surface being worked. The oscillating effect is caused by the distortion of the resilient cushion 25, by the driving torque and the constant lateral movement of the disc 28 across the frictionally resistant surface being abraded and produces a highly desirable free floating action or lap grind.

Since the cushion 25 of the oscillator is designed primarily to function properly with comparatively light loads of back pads 26 and abrasives 28, the operation with heavier loads or higher speeds will result in exaggerated oscillation beyond the point of usefulness. Accordingly, the mass of cushion 25 must be restrained. For most uses the restraint of the member 32 is sufficient to restrict oscillatory movement to useful limits. Likewise, the member 32 adds a safety feature at higher loads and speeds by intercepting the shear plane of the cushion 25. As illustrated in Figure 3, the gyro-oscillation of

the cushion 25 should be restricted to prevent the increased momentum of the greater weight load getting out of easy manual control by the operator.

5 The present resilient coupling may be adapted to a wide range of functioning, from the coarse heavy wheel 31 grinding to fine abrasive or polishing attachments such as the disc 28, by the use of the accessory shown in Figure 2. This 10 consists of the cushion constricting cup having the cylindrical band 32, integral with the end 33, having the axial hole 34, encircling the drive shaft 13, and counterbored to fit the hub of the head 15. The band 32 encircles the exposed 15 periphery of the cushion 25 in frictional contact therewith and has the internally beveled edge extending forward to a point spaced from the margin of the flange 20 of the driven head. This band prevents and restricts excessive lateral 20 distortion of the cushion 25 under heavy loads and the variable R. P. M. of the driven head under variable working loads, as well as increasing the modulus. These cups may be provided 25 with different longitudinal width of bands 32 and may be applied to the coupling in accordance with the load to be applied to the driven head 19, if desired, to secure differing effects and results.

The auxiliary stud 30' replaces nut 30 and 30 is provided for mounting the hollow grinding wheel 31 onto the driven head 19. It consists of the threaded end 38, which may be screwed into the internal thread in this head, up to the tapered flange 43, which is adapted to fit flush 35 in the dished head. The threaded stud end 39 extends through the wheel 31 locking the same against the flat face of flange 43 either by threads in wheel bushing or by the hexagonal nut 46, in the usual manner. The driving 40 torque screws tighten these various threaded elements.

This solid wheel 31 is particularly adaptable 45 to the surfacing of stone, terrazzo, marble and similar building walls, floors, steel decks and the like, where a flat plane without score lines is essential. Because of its shock absorbing and gyro-oscillating qualities a sufficient mass of resilient cushion 25, is essential to prevent concentric scoring of the surface being worked, the 50 constricting cup band 32 is superior to a mere reduction in the quantity mass of the cushion 25 in that it becomes variable and requires a different size for each different use. If needed, the width of the band 32 relative to the exposed 55 periphery of the cushion 25 may be chosen in accordance with the gyro-oscillating qualities desired.

The dynamic balance of the present resilient 60 coupling with its restricted oscillation and increased modulus is such that the face of the abrasive disc 28, or the face of the wheel 31, may be operated flat on the surface being worked without causing concentric score lines or the machine deviating from its working location without manual control, other than to balance the overhanging weight of the motor relative to the plane of the worked surface. This greatly reduces the skill and labor required when the backing 65 26 is flexed or the wheel 31 applied to the surface off its axial center. No axial distortion of the drive shaft results with consequent damage to bearings and gears. This is due largely to the distribution of the mass of the cushion between the driving and driven heads 15 and 19.

The correction of axial distortion is not interfered with.

I claim:

1. An oscillating resilient coupling comprising a driving head and a driven head arranged in coaxial spaced relation, a central hub on each said head, said hubs extending inwardly toward each other, a radial flange on the inner end of each said hub, said flanges being arranged in parallel to each other in spaced relation and 10 perpendicular to the axis of the coupling, a body of rubber-like material including a web thereof passing between said flanges, disposed between and bonded to said heads and flanges to form a unitary structure capable of transmitting torque, means for attaching the driving head to the spindle shaft of a driving element, means for attaching a driven element to said driven head, and a cup member surrounding one of said heads and extending axially to partially surround said body leaving a portion of the periphery exposed.

2. An oscillating resilient coupling comprising a driving head and a driven head arranged in coaxial spaced relation, a central hub on each said head, said hubs extending inwardly toward each other, a flange on the inner end of each said hub, said flanges being arranged opposed to each other in spaced relation, a body of resilient

material including a web passing between said flanges, disposed between and bonded to said heads and flanges to form a unitary structure capable of transmitting torque, means for attaching the driving head to the spindle shaft of a driving element, means for attaching a driven element to said driven head, and a cup member surrounding one of said heads and extending axially to partially surround said body leaving a portion of the periphery thereof exposed.
